TUBE CLEANING DEVICE

George W. Allen, Boston, Mass., assignor to B. F. Sturtevant Company, Boston, Mass., a corporation of Massachusetts

Application June 4, 1937, Serial No. 146,446

4 Claims. (Cl. 15—104.05)

The present invention relates to tube cleaning devices, and more particularly to a tool for loosening and removing foreign matter from the interior of boiler tubes and the like.

5 The conventional method of cleaning boiler tubes involves the use of a brush or scraper or a combination of the two by which the foreign matter may be loosened and, by repeated reciprocation of the cleaning tool along the tube, scraped out of the tube at each end. Such method is unsatisfactory, due to the time required to remove the loosened matter from the tube and because of the necessity for collecting the material from each end of the boiler after the scraping 10 operation has been performed.

15 The present invention has for its object the provision of a tube cleaning device of novel and improved construction which enables the loosening and removal of foreign matter from a tube 20 at a single passage of the device through the tube.

Another object of the invention is to provide a tube cleaning tool of simple construction and arrangement in which the removal from the tube of foreign matter loosened by the device is performed pneumatically and in a more effective 25 manner than heretofore.

With these and other objects in view, a feature 30 of the invention comprises a tube cleaning tool which, in addition to brushing and scraping members for loosening the foreign matter, is provided with a suction inlet adapted to be connected to a suction device located outside the tube for withdrawing the foreign matter from the tube, the suction inlet being so positioned in the device 35 that large quantities of comparatively heavy material may be readily drawn into the inlet and carried out of the tube.

Another feature of the invention comprises a tube cleaning device provided with a suction inlet and having baffling means adapted to cooperate therewith whereby the air flowing to the inlet may be concentrated in a stream of high velocity adjacent the wall of the tube, with the result 40 that the effectiveness of the suction in removing the loosened foreign matter is substantially increased.

A further feature of the invention comprises a tube cleaning device adapted to be reciprocated within and along a boiler tube and the like, the 45 tool being constructed and arranged so that it may be drawn back into the tube without difficulty in the event that it is passed entirely through the tube and emerges at the far end thereof.

In the drawing illustrating a preferred form of 50 the present invention, Fig. 1 is a sectional view of the tube cleaning device in operative position within a boiler tube, and showing a portion of the tubular actuating handle of the device, and Fig. 2 is a view illustrating the device and its asso-

ciated apparatus arranged to carry out the tube cleaning operation.

The embodiment of the tube cleaning tool shown in the drawings and embodying the invention comprises a scraping member 4 having a flange portion 6 and a hub portion 8. The flange is of a diameter only slightly less than the interior of the tube, in order that positive scraping action may be afforded around the entire interior of the tube at a single passage of 10 the cleaning device therethrough.

The rear face of the flange is beveled around its outer edge 9, as indicated in Fig. 1, not only for the purpose of providing a narrow and hence more effective scraping edge, but also to render 15 the device self-centering to enable it readily to be drawn back into the tube in case it is pushed entirely through the same and out the far end thereof.

20 The scraping member is provided with an aperture 10 in the flange portion 6 and extending through the hub 8, said aperture serving as a suction inlet through which the loosened foreign matter is removed from the tube during the cleaning operation. The suction inlet is preferably 25 positioned eccentrically with respect to the flange 6, so that with the tool properly oriented within the tube to position the suction inlet at its lowest point, the said inlet is brought into close proximity to the loosened material which naturally 30 gravitates to the bottom of the tube, thus enabling the effective removal of large quantities of material without requiring a high degree of suction.

35 The hub 8 of the scraping member is adapted to be received within one end of a tubular member 12 which serves both as an actuating handle for reciprocating the cleaning device along the interior of the tube, and also as a suction conduit through which the foreign material is carried 40 from the suction inlet 10. The handle is secured to the scraping member by any suitable means, illustrated in the drawing as a set screw 14 in the handle 12 and engaging an annular groove 16 in the hub 8.

45 Suction is imparted to the inlet 10 in the scraping member by a suitable suction device 18 located outside the tube and connected by a flexible hose 20 to the outer end of the tubular handle 12. The suction means illustrated in Fig. 2 comprises 50 a well known portable unit of commercial type, having a motor driven suction fan and a self-contained dirt collecting bag or receptacle.

55 Mounted upon and in spaced relation to the scraping member 4 is a baffle plate or disk 22, which is adapted to cooperate with the scraping member to increase the suction of the stream of air flowing to the inlet 10. The baffle plate is of somewhat smaller diameter than the flange 6, and is concentrically positioned with respect 60

thereto by means of mounting screws 24 and spacing sleeves 26. By preventing the free passage of air to the suction inlet through the central portion of the tube, the baffle plate serves 5 to concentrate the flow of air in a stream of high velocity adjacent the walls of the tube, insuring that the tube will be completely cleared of all foreign matter loosened by the device.

For loosening soot and similar adherent material, the cleaning device is provided with a brush member 28 at the forward end thereof. The brush is made up of stiff wire bristles slightly longer than the diameter of the tube and which are gripped in a core 30 of twisted wire. The 10 core is clamped in a short length of tubing or pipe 32 threaded at one end and screwed into a tapped hole in the center of the baffle plate 22. Preferably a space is provided between the brush and the baffle plate, as illustrated in the drawings, 15 in order that the brush may not interfere with the acceleration of the air stream adjacent the baffle plate.

The device of the invention is utilized to carry out the tube cleaning operation in a boiler or the 20 like by attaching the tool to one end of the tubular handle 12, the set screw 14 being tightened just sufficiently to engage the annular groove 16 without restricting relative rotation of the parts. The handle may comprise either a single section 25 of length at least equal to the length of the tubes to be cleaned, or several sections with suitable interlocking joints for convenience in handling, or for use where space is limited. The other end of the handle is attached to the flexible hose leading 30 to the suction unit, and the fan motor started.

The tool, before its insertion in the tube, is rotated relative to the handle to bring the suction inlet 18 to its lowest point with respect to the flange 8, and the set screw tightened to lock the 40 parts against relative rotation. The device is then inserted in the tube and advanced to the far end thereof by short reciprocating strokes. To insure that the entire length of the tube may be effectively cleaned, the tool is preferably 45 pushed entirely through the tube and out the other end. The device may be drawn back into the tube without difficulty even though the far end thereof is inaccessible, due to the beveled rear edge 9 which renders the device substantially 50 self-centering for rearward movement when properly oriented as described.

During the advancing or cleaning movement of the device the brush 28 loosens and stirs up the 55 soot and ashes or the like, the lighter particles of which are caught up by the stream of air being drawn through the brush to the suction inlet. As the air stream passes around the baffle plate, its velocity increases, due to the reduction in 60 area of the passage, the added suction drawing the heavier particles of foreign matter to the inlet. These particles, together with the relatively heavy fragments which are dislodged by the positive scraping action of the flanged member are 65 readily drawn into the suction inlet by reason of its position adjacent the bottom of the tube, since the foreign matter naturally gravitates to the low portion thereof.

While the invention has been illustrated and 70 described as embodied in a specific construction and arrangement, the invention is not to be understood as being so limited, but extends to other

constructions and arrangements within the scope of the appended claims.

Having thus described the invention, what is claimed is:

1. A device for cleaning the interior of tubes and the like comprising a scraping blade member substantially the diameter of the interior of the tube and provided with a suction inlet adapted to be connected to a suction device, and an imperforate baffle plate spaced from and supported by 10 said member adjacent the suction inlet and of somewhat lesser diameter than the member to form an open annular air passage adjacent the walls of the tube to cause the stream of air to flow through said passage at high velocity over 15 the surface of said walls to said suction inlet.

2. A device for cleaning the interior of tubes and the like comprising a scraping member substantially the diameter of the interior of the tube and provided with a suction inlet adapted to be 20 connected to a suction device, an imperforate baffle plate spaced from the scraping member and of somewhat lesser diameter than the same to form an open annular air passage adjacent the walls of the tube to cause the stream of air to flow 25 through said passage at high velocity over the surface of said walls to said suction inlet, and a brush member mounted in proximate spaced relation to the baffle plate and on the opposite side thereof from the scraping member and the suction inlet, thereby to loosen the lighter particles of foreign matter on the wall so they may be caught up by the air stream passing through the brush while the heavier particles are cleared 30 therefrom by the high velocity annular air stream 35 passing around the baffle plate.

3. A device for cleaning the interior of tubes and the like comprising a scraping blade member substantially the diameter of the interior of the tube, a baffle plate spaced from and supported 40 by said member and of somewhat lesser diameter than the member to form an open, annular air passage adjacent the walls of the tube, and a suction passage adapted to be connected to a suction device at one end and having an inlet port 45 in fluid communication with the space between said scraper and said baffle.

4. A device for cleaning the interior of tubes and the like, comprising a scraping blade member substantially the diameter of the interior of 50 the tube and having a suction inlet passage disposed in the front face thereof, an imperforate baffle plate of somewhat lesser diameter than the scraping member, relatively slender supports carried thereby for supporting the baffle plate in 55 proximate spaced relation to the scraping member opposite the suction inlet therein to form an open, annular air passage adjacent the walls of the tube to cause the stream of air to flow 60 through said passage at high velocity over said 65 walls to the suction inlet, and a brush member supported by the baffle plate on the opposite side thereof from the scraping member, said scraping member having provision for connection thereto of tubular means by which the device may be reciprocated along the tube and through which suction 70 may be applied to the suction inlet from a suction device outside the tube, to cause all the cleaning air to pass through the brush and along the walls of the tube to the suction inlet.

GEORGE W. ALLEN.
